UNITED STATES PATENT OFFICE.

JOHN D. ROBERTS, OF OAKMONT, PENNSYLVANIA.

ODOMETER.

No. 845,820.

Specification of Letters Patent.

Patented March 5, 1907.

Application filed May 22, 1906. Serial No. 318,161.

To all whom it may concern:

Be it known that I, JOHN D. ROBERTS, a citizen of the United States, residing at Oakmont, in the county of Allegheny and State of Pennsylvania, have invented certain new and useful Improvements in Odometers, of which the following is a specification.

My invention relates to registering devices, and particularly to that class known as "odometers" and similar devices for indicating revolutions either directly or reduced to standards of measurement and fractions thereof.

The principal object of my invention is to provide an instrument of this class which will be simple, and positive in its action and at the same time durable and compact in its construction.

Another object of my invention is to produce an instrument which will register accurately, and this I accomplish by positive locking of all of the idle register-cylinders and by the provision in the lever-arm for a reversal of direction of the object to which the device may be attached. These two features respectively prevent spinning or displacement of the register-cylinders and reduction of the register by the reversal of the direction of the vehicle or other object to which the instrument may be attached.

In the accompanying drawings, which form part of this specification, Figure 1 is a plan view of an odometer embodying my invention. Fig. 2 is a vertical section viewed from the lever-arm end of the instrument and shows the fore part of the case cut away. Fig. 3 is a longitudinal section of the case in the direction of the shaft with the mechanism in elevation. Fig. 4 is a sectional detail through the line I I of Fig. 3. Fig. 5 shows in enlarged detail a group of register disks or cylinders and their intercommunication. Fig. 6 is a view of one face of the register disks or cylinders, and Fig. 7 is a section through the shaft and shows the reverse face of one of the said register-cylinders and its adjacent collar carrying the pinion or star-wheel through which movement is transmitted to the next cylinder at intervals.

In the particular description of my invention I have for convenience shown it as applied to an odometer, and I will so describe it, although I do not wish to confine myself to that embodiment.

Referring to the drawings, a case 1 is at-

tached to a base 2 by suitable lugs 3 and screws 4, said base having openings 5 5 for attachment to the vehicle or other object. A shaft 6, passing through the bearings 7, extends into a sleeve 8, which is fixed in the side of the case 1. An arm 9, jointed at 10 to bend in one direction only and held normally straight by a suitable spring 11, is fixed to the projecting end of the shaft 6. Inside the casing an arm 12, fixed on the shaft 6, has a pawl 13, held by the spring 14, in engagement with the teeth of the ratchet-wheel 15, mounted on the side of the case 1. A spiral spring 16 holds said arm 12 in its normal position against the pin 17, set in the side of the case 1. A spring-pawl 18, attached to base 2, engages ratchet-wheel 15 and prevents backward movement of same. A pinion 19, fixed to said ratchet-wheel 15, engages the gear-wheel 20, which is rev- 75 olutely mounted on the sleeve 8 and is coupled rigidly to the adjoining register disk or cylinder 21^a by pins or other convenient method or may be made integral therewith.

The register disks or cylinders 21^a 21^b 21^c 80 21^d 21^e are all identical in construction, though the disk 21^a may be made without the radial teeth on the face adjacent to the gear 20, they being superfluous in this one cylinder. These register disks or cylinders 85 21^a-21^e are revolvably mounted on the sleeve 8 and have on one face the radial teeth 22, and on the rim or flange 23 are placed the register-numerals.

On the inner face of each disk or cylinder is 90 placed a single projecting tooth 24 with an indentation 25 on either side thereof, the rest of said inner face being plain. Between the disks or cylinders are placed collars 26, held rigidly on sleeve 8 by set-screws 27 and having the pinion or star-wheel 28 meshing with the teeth 22 on the one side and at intervals being engaged by the single tooth 24 of the adjacent disk.

The opening 29, covered by glass or other 100 transparent material, permits the register-numerals on the cylinders to be read in rotation, one line of figures only being in view. A striker 30 is attached to the wheel of the vehicle or other object to engage the lever- 105 arm 9.

The operation of my device is as follows: The instrument is conveniently attached to the vehicle or other object and at each revolution of the wheel the striker engages the 110

lever-arm 9, which turns the shaft 6, moving forward the pawl 13 in engagement with the ratchet-wheel 15. The movement of the ratchet is transmitted, through the pinion 19 and gear-wheel 20, to the register disk or cylinder 21^a, which in the particular embodiment shown is marked with fractions of a mile upon its rim, the proportions of the reduction-gears being determined with relation to the diameter of the wheel of the vehicle, as is the usual practice.

The star-wheel 28 is normally in the position shown in Fig. 5, disk 21^b, wherein two of its teeth are shown meshing with the teeth 15 of the register-disk next farthest from the lever-arm end of the instrument and having two teeth resting against the plain face of its complementary register-disk. In this position it is apparent that the star-wheel is 20 locked and holds immovable the register-cylinder next farthest from the lever-arm end. Once in each revolution of disk 21^a its single tooth 24 engages the star-wheel, and by reason of the indentations 25 25 the said star-wheel is free to revolve and advance the next register one division of the scale. The same is accomplished with each successive disk or cylinder and its star-wheel. Once in each complete revolution the next succeeding register-cylinder is moved one division and is then 30 locked rigidly during the remainder of the revolution.

The circumferential rims of adjacent disks bear against each other, thereby excluding 35 dust and making a very compact instrument. The elbow in the lever-arm 9 permits re-

versal of the direction of the vehicle without affecting the register of the instrument.

Having thus described my invention, what I claim as new, and desire to protect by Letters Patent, is—

In an odometer, the combination with a case having a sleeve fixed therein and a shaft projecting therefrom, of a plurality of register-disks mounted on said sleeve and each 45 provided with a circumferential laterally-projecting flange to provide a circumferential surface for register-numerals, radial teeth on one face of said disks, a smooth surface with a single tooth and an indentation on 50 either side of said tooth on the opposite face of said disks, a fixed collar on said sleeve between adjacent disks, a star-wheel on said collar at right angles to said disks and having some of its teeth meshing with the teeth of 55 one disk while its opposite teeth normally bear against the smooth surface of the complementary disk, said star-wheel being free to turn only when engaged by the single tooth on said complementary disk and in mesh with the aforesaid indentations, a train of gears connecting one of said cylinders with said shaft, and a jointed rocker-arm on said shaft to transmit motion in one direction only, substantially as and for the purposes set forth. 60

In testimony whereof I have affixed my signature in presence of two witnesses.

JOHN D. ROBERTS.
